UNITED STATES PATENT OFFICE.

CLARENCE V. ELLIOTT, OF LOS ANGELES, CALIFORNIA.

CARBURETOR.

Application filed January 21, 1924. Serial No. 687,646.

This invention relates to carburetors for automobiles, and is more particularly directed to a carburetor having a simple construction and relatively few parts.

Carburetors now employed in connection with internal combustion engines are, for the most part, of very complicated structure with fine adjustments that are easily rattled or jarred out of place, greatly affecting the operation of the car.

An object of this invention is to produce a carburetor having a very few parts.

An object of this invention is to produce a carburetor in which there is required no adjustment.

An object also is to provide a carburetor having a metering orifice so constructed that change of temperature of the liquid does not affect the flow of liquid through the carburetor.

Other objects will be apparent from the following detailed description of a preferred embodiment of this invention, of which the accompanying drawings are a part.

25 In the drawings:

Figure 1 is a sectional side elevation of a carburetor embodying this invention.

Fig. 2 is a sectional end elevation thereof taken substantially on the line 2—2 of Fig. 1.

30 Fig. 3 is a sectional side elevation showing a modified embodiment of this invention, and showing a needle valve adjustment for the idle flow of fluid when a main intake valve is closed.

35 Fig. 4 is a sectional end elevation of the carburetor shown in Figure 3 and taken substantially on the line 4—4 Fig. 3.

Fig. 5 is a sectional plan view of the embodiment of the invention shown in Figure 3.

40 Fig. 6 is an enlarged sectional view of the metering orifice and flow tube as used in connection with this invention.

45 Referring to the drawings, 1 represents the body of the carburetor, which is a hollow member with a Venturi-shape passageway 2. 3 represents a butterfly throttle of the usual construction for controlling the amount of mixture passing through the engine. 4 represents a choke valve for temporarily enriching the mixture when starting the engine. 5 is a fuel container attached to a cover 6 by any suitable means, as shown at 7. The cover 6 may be a part of the body 1 or a separate piece fastened to the body 1 by any means, such as the screws 8.

The fuel enters the float bowl 5 at 21 and

flows through a small opening 22. When the fuel reaches a predetermined level, a float 10 is raised against a lever 20, the said lever 20 being supported at one end by the screw 18. When said lever 20 is raised by the float 10, the said lever 20 pushes the needle 19 against its seat 23 and prevents the further inflow of the fuel. This mechanism serves to keep a practically constant level of the fuel in the float bowl 5; however, this mechanism differs little from that now used in the art and no novelty is claimed for it.

12 is a hollow screw which may be screwed or otherwise secured to the float bowl cover 6. Held between the head of the screw 12 and the float bowl cover 6 is a length of tubing 11, said tubing 11 having an orifice 13 in its lower end and a second orifice 17 at the upper end. The orifice 17 might be replaced by two orifices of equal area, or might be drilled in the float bowl cover. The hole 13 is a metering orifice for the admission of the fuel from the fuel container 5 into the interior of the hollow tubing 11, while the orifice 17 admits air into the interior of the said tubing 11; air being admitted to the upper portion of the fuel container 5 through a hole 25 in the cover 6.

The fuel passing through the orifice 13 is drawn through the series of orifices 14 positioned in the lower portion of the hollow screw 12. Air drawn through the orifices 17 enters the hollow screw 12 through a series of holes 15 positioned in the screw 12 near the level of the fuel in the container 5. The holes 16 positioned intermediate between holes 14 and 15 and the hollow screw 12 serve to allow either the fuel or air, or a mixture of fuel and air, to be drawn into the interior of the hollow screw 12 at this point. The fuel, having been admitted into the interior of the hollow screw, is drawn upward through the screw 12 by the partial vacuum created by the engine and is discharged either through the by-pass 24 or through the single opening 27.

In the construction of this carburetor, I have found that the correct relation of the parts to eliminate the necessity of fine adjustments to be approximately in the following proportions:

The Venturi-shape passage 2 should be .694 inches in diameter; the discharge opening 27 should be .156 inches in diameter; the holes 14, 15 and 16 and the hollow tube 12 should be .042 inches in diameter; the metering orifice 13 should be .039 inches in diameter; the

orifice 17 should be .042 inches in diameter; and the by-pass discharge 24 should have a diameter of .042 inches in diameter.

These sizes are cited to more easily enable one skilled in the art to construct a carburetor in accordance with the discovery embodied in this invention. By this relation of parts, I have found that there is required no adjustment for idling, nor is there required any adjustment of the discharge openings 27.

It is to be understood that the sizes herein specified can be varied within reasonable ranges, retaining, as near as possible, the proportions specified.

15 In the embodiment of this invention shown in Figures 3, 4 and 5, I prefer to use a tube 5' pressed in the body 1 so as to extend across the restricted metering orifice 2 of the air passageway. In the sides of the tube 5' are 20 one or more holes 6', which holes, combined, are to have approximately the same discharge area as the discharge opening 27 shown in Figure 1. One end of the tube 5' is in communication with the interior of the hollow 25 screw 12. The other end of the tube 5' connects with the by-pass passageway 23' formed in the body 1.

The by-pass 23' has an outlet 24', into the space between the throttle and the engine. 30 The size of the opening between the by-pass and the tube 5' may be regulated by the screw 29'; however, I have discovered that by adhering to the relation of parts heretofore specified, the screw 29' is not a necessary part 35 of this invention.

The operation of this carburetor is as follows:

When the engine is cranked, the throttle 3 is partly open and the choke 4 is partly closed. A suction will be produced in the air passageway and will be transmitted through the by-pass 24 and the discharge opening 27 or the holes 6' to the interior of the tube 5', thence to the hollow screw 12. 45 Fuel will be drawn through some of the holes in the screw 12, to which it is supplied by the metering orifice 13. Air, at the same time, will be drawn through the upper hole 15, to which it is supplied by the hole 17 and the 50 hole 25 in series. The mixture of fuel and air formed inside the hollow screw 12 will be drawn up and discharged into the main air passageway through the discharge opening 27 or hole 6', or through the by-pass opening 55 24, depending upon the position of the throttle.

The principle embodied in this invention is that the metering orifice 13, cut in the thin hollow tube 11, allows the flow of the fluid fuel into the interior of the tube 11 without altering the volume of fluid fuel admitted due to change in temperature or density of the fluid.

The holes 15 positioned in the screw 12 approximately at the level of the fuel in the

container, cause a more efficient mixing of the fluid fuel with air, admitted through the holes 17 and 25 in series, securing a mixture of fuel and air that is more easily drawn into the engine, on starting the engine, or on acceleration of the engine.

Having fully described a preferred embodiment of this invention, it is to be understood that I do not wish to be limited to the construction herein disclosed, which may be varied in detail without departing from the spirit of the invention, as pointed out in the appended claims:

What I claim is:

1. In a carburetor, the combination of a body, a passageway through the body, a fuel container, means for admitting fuel into the fuel container, means for controlling the flow of fuel into the fuel container, means for admitting air into the fuel container, an inner tube having a fuel inlet, and upper and lower air inlet ports, an outlet for the inner tube into the passageway in the body, a throttle valve mounted in the passageway, a by-pass formed in the body in communication with the inner tube and extending to the discharge side of the throttle valve, an outer tube exterior of and spaced from the inner tube, a fuel inlet formed in the wall of said outer tube, and means whereby the air admitted to the fuel container can enter into the space between the inner and outer tube.

2. In a carburetor, the combination of a body, a passageway formed through the body, a fuel container, means for admitting fuel to the container, means for controlling the admission of fuel to the fuel container, means for admitting air into the fuel container, an inner tube having a fuel inlet port and spaced air inlet ports, one of which inlet ports is located above the normal level of the fuel in the said fuel container, an outlet for the inner tube into the passageway formed through the body, a throttle valve mounted in the passageway, a by-pass in communication with the inner tube and the passageway on the discharge side of the throttle valve, an outer tube exterior of and spaced from the inner tube, a fuel inlet formed in the wall of the outer tube, and means whereby the air admitted to the fuel container can enter into the space between the inner and outer tubes.

3. In a carburetor, the combination of a body, a passageway formed through the body, a tube extending across the passageway, outlet ports formed in the tube in the passageway, a throttle valve mounted in the passageway, a by-pass from the said tube to the passageway and extending to the discharge side of the throttle valve, a fuel container, means for admitting fuel into the fuel container, means for controlling the admission of fuel into the container, means for admitting air to said fuel container, an outer tube, an orifice in the outer tube below the normal fuel level, an

inner tube within and spaced from the outer tube, means whereby the air admitted to the fuel container can enter into the space between the inner and outer tubes, an outlet 5 from the inner tube to the said tube extending across the said passageway, and a plurality of orifices in the inner tube, some of which orifices are above the fuel level in the container.

- 10 4. In a carburetor, the combination, of a body, a passageway formed through the body, a fuel container, means for admitting air into the fuel container, means for admitting liquid fuel into the liquid container, means for controlling the admission of liquid fuel into the liquid container, an outer tube mounted within the container and having a fuel orifice, an

inner tube mounted within and spaced from the outer tube, air and fuel orifices formed in the said inner tube, a tube extending from 20 the inner tube across the passageway, discharge holes formed in the latter said tube in the said passageway, an outlet from the inner tube to the said tube extending across the passageway, a by-pass communicating with 25 the inner tube and extending to the discharge side of the said body beyond the throttle valve, and means whereby the air admitted to the fuel container can enter the space between the inner and outer tubes. 30

Signed at Los Angeles, California, this 9th day of January, 1924.

CLARENCE V. ELLIOTT.
